UNITED STATES PATENT OFFICE

2,309,209

PACKAGE FORMING AND FILLING
APPARATUSFrank D. Palmer, Chicago, Ill., assignor to Kraft
Cheese Company, a corporation of Delaware

Application July 31, 1939, Serial No. 287,498

36 Claims. (Cl. 93—3)

This invention relates to a method and apparatus which produces from blank sheet material a container, fills the container, closes and seals the same, and then ejects the filled package from the machine.

The main objects of the invention are to provide an improved method and apparatus for automatically and continuously producing from blank sheet material, containers, and filling and closing the same rapidly and economically, so as to reduce to a minimum the cost of packaging of the product concerned; to produce such mechanism which will operate continuously with a minimum of attention from an operator; to produce such an improved method and apparatus which will occupy a minimum of floor space; to provide a method and apparatus in the character indicated which will produce a small sized but effectively sealed package, particularly but not exclusively adapted for the packaging of powdered, granular, or other similar materials which it is desired to preserve indefinitely in their original condition as to moisture content; and in general it is the object of this invention to provide an improved packaging method and apparatus.

Other objects and advantages of the invention will be understood by reference to the following specifications and accompanying drawings (18 sheets), wherein there is disclosed a method and apparatus according to a selected form of the invention.

In the drawings:

Figure 1 is a top plan view;

Figure 2 is a side elevation of a portion of the mechanism shown in Figure 1;

Figures 3 and 4 are sections respectively on the lines 3—3 and 4—4 of Figure 1;

Figures 5, 6, and 7 are sections respectively on the lines 5—5, 6—6, and 7—7 of Figure 3;

Figure 8 is a section on the line 8—8 of Figure 7;

Figure 9 is a section on the line 9—9 of Figure 7; but showing the parts in an advanced and changed position;

Figure 10 is an enlargement of a part of Figure 9, but showing a changed position of the parts;

Figure 11 is a front elevation of a part of the mechanism shown in Figure 9.

Figure 12 is a section similar to Figure 9, but showing the parts in an advanced and changed position;

Figure 13 is a section on the line 13—13 of Figure 9;

Figures 14 and 15 are sections similar to Fig-

ure 13, but showing changed positions of the mechanism;

Figure 16 is a section on the line 16—16 of Figure 14;

5 Figure 17 is a section on the line 17—17 of Figure 13;

Figure 18 is a section on the line 18—18 of Figure 15;

10 Figure 19 is a section corresponding to a part of Figure 9, but on an enlarged scale and showing the parts in a changed position;

Figure 20 is a section similar to Figure 19, but showing a further changed position;

Figure 21 is a section on the line 21—21 of Figure 4;

Figure 22 is a diagrammatic plan section showing certain cam operating mechanism;

Figures 23, 24, and 25 are perspectives of certain elements of the mechanism;

20 Figure 26 is a diagrammatic plan section showing certain cam operating mechanism;

Figure 27 is an electric circuit diagram;

Figure 28 is a section on the line 28—28 of Figure 9;

25 Figure 29 is an elevation of cam mechanism shown in Figure 28;

Figure 30 is a section on the line 30—30 of Figure 28;

Figure 31 is a section on the line 31—31 of Figure 28;

Figures 32 and 33 are sections respectively on the lines 32—32 and 33—33 of Figure 9;

Figure 34 is a perspective of an element of mechanism shown in Figure 33;

35 Figure 35 is a section on the line 35—35 of Figure 8;

Figure 36 is a plan of a sheet of material from which containers are to be formed and showing the initial preparation of the sheet;

40 Figures 37 to 42 inclusive are perspectives illustrating successive steps in the formation and closing of the container.

Referring now to the drawings and initially to Figures 1, 2, and 3 thereof, the apparatus herein

45 referred to comprises a frame structure consisting of supporting legs such as indicated at 50, a lower stationary spider or frame 51 and a central, upwardly extending stationary tubular post 52. The lower frame member 51 is provided with

50 a laterally extending part 53, which supports upwardly extending frame members 54, which in turn support wrapper feeding mechanism. Supports 55 and 56 for supply rolls S of wrapper material are suitably mounted on upstanding supporting posts 57—57 which are suitably

mounted in conveniently accessible parts of the frame. The two supply roll supporting devices are provided so that a reserve supply roll may be ready for feeding into the mechanism immediately upon exhaustion of the other roll, thereby to avoid the necessity of interrupting the operation of the machine for the purpose of replacing an exhausted supply roll of wrapper material. The wrapper material may be of any suitable type, for example, metal foil, "Pliofilm," "Paracote," or other materials which may be unitized to themselves by the application of heat or pressure or both, either because of their inherent nature or because of suitable coatings of cementitious material applied thereto.

The web T of such wrapper material is carried downwardly from either of the supply rolls thereof and threaded between upper and lower feed rolls 58 and 59 respectively. The feed roll 59 is suitably journaled in frame work of the apparatus and it is continuously driven by means of gear connection as shown to a shaft 60 which is connected by suitable means such as chain and sprockets as shown to a shaft 61. The shaft 61 is continuously driven by suitable connections such as sprockets and a chain as shown to a shaft 62 which is in turn continuously driven by similar driving connections to a shaft 63 which may be representative of any suitable source of power, for example, the output power shaft of an electric motor driven speed reducing unit 64. An electric motor directly connected to the speed reducing unit is indicated at 65.

The upper feed roller 58 is journaled in suitable bearing blocks mounted for vertical sliding movement and is normally urged downwardly by means of a spring arrangement such as indicated in Figures 2 and 3. The roller 58 is thus operative to press the web T into driving engagement with the driven roller 59 so that rotation of the latter feeds the web forwardly. The web is carried forwardly between the feed rollers 58 and 59 and is threaded between another pair of feed rollers 66 and 67 of which the lower feed roller 67 is continuously driven by suitable sprocket and chain connections and as indicated to a shaft 68 which is in turn continuously driven by suitable chain and sprocket connections to a shaft 69. The shaft 69 is geared to the shaft 70 as best shown in Figure 3 so as to be thereby continuously driven. The upper roller 66 is mounted so as to be movable upwardly but is normally urged downwardly towards the lower roller 67 by spring means as indicated in Figures 2 and 3.

Between the said feed roller pairs, the web T is guided over an upwardly humped supporting plate 70 and a flat plate 71, and between side guides such as indicated at 72. The web T issuing from between the feed rollers 66 and 67 passes over a table bar 73, the free edge 74 of which constitutes one cutting member of mechanism for shearing the web T into separate wrapper units hereinafter designed "W".

The other cutting member of the shearing mechanism comprises a blade 75 which is carried by a crosshead 76, the latter being vertically slidably mounted on upstanding posts 77-78 which are suitably supported on the bed plate 79 of the frame structure of the apparatus (see also Figure 6). The crosshead 76 carries a holding member 79 which is suitably mounted in the crosshead for vertical movement relative thereto and which is normally urged downwardly by a suitable spring arrangement as indicated in Fig-

ure 3. The member 79 is adapted to hold the web T in fixed position against the member 73 during the time that the shear members 74 and 75 are co-operating to sever the web to form the separate wrapper sheets.

The crosshead 76 also carries an embossing or creasing die 80 which is suitably vertically slidably mounted on the crosshead or on extension brackets carried thereby, the said die being normally urged to move downwardly relative to the crosshead by suitable spring means as best shown in Figures 3 and 6. The plate 71 which is disposed immediately below the creasing die 80 is provided with grooves or the like for cooperating with ridges or the like carried by the upper die member 80 for effecting creasing of the web.

During the shearing and embossing or creasing operation it is of course necessary that the web T remain stationary. That portion of the web which is located between the creasing dies 71 and 80 and therebeyond is permitted to remain stationary by effecting separation of the feed rollers 66 and 67 as an incident to the descent of the crosshead 76. For this purpose there is provided at opposite ends of the roller 66, arms such as indicated at 81 which are pivoted intermediate their ends as shown at 82. One end at each of said levers 81 extends beneath a portion of the shaft of the roller 66 and the other end of each lever 81 is adapted to be engaged by an adjustable member in the form of a screw 83 which is carried by the crosshead 76. It will be apparent that when the cross head 76 is lowered, the screws 83 may be caused to engage the underlying end portions of the levers 81 so as to rock the same and thereby effect upward adjustment of the roller 66 relative to the driven roller 67. In this manner driving contact between the web T and the driven roller 67 will be disengaged. The feed rollers 58 and 59 continue, however, to advance the web T. The upwardly humped guide member 70 serves to direct the web into an upwardly directed loop intermediate the feed rollers 58 and 59 and the creasing dies 71 and 80 during such time as the latter are in cooperative relation. Upon upward or return movement of the crosshead 76, the levers 81 are of course released and the feed roller 66 is permitted to restore driving engagement between the web T and the driven roller 67. As shown in the drawings, the ratios of the pitch diameters of the sprockets by means of which the roller 67 is driven, is such that said roller 67 is driven at an accelerated speed so as to enable the feed rollers 66 and 67 to take up the slack in the web T.

The crosshead 76 is reciprocated vertically by means of links 92-92 (Figure 6) which are connected at their upper ends to the crosshead 76 and at their lower ends to crank pins 93-93 carried by the continuously driven shaft 61.

The drive of the shaft 61 is through the agency of a disengageable clutch arrangement which comprises a collar 94, is keyed to the shaft 61, a transversely slideable clutch dog 95 carried by the collar 94, and a clutch part 96 formed integrally or rigidly connected to the sprocket 97 which is rotatable on the shaft 61. The sprocket 97 is connected by means of a chain and another sprocket to the driven shaft 62. The clutch dog 95 is normally urged by a spring 98 into driving engagement with the driven clutch part 96 but it is adapted to be disengaged therefrom by means of a clutch operating member 99 which is carried by an arm 100. The arm 100 is pivoted as shown at 101 to a conveniently located

frame part and its other end is connected by means of a link 102 to the core of a solenoid 103. Under certain conditions which will hereinafter be explained, the solenoid 103 may be deenergized (or in the alternative energized) to cause or permit the lever 100 to move downwardly so as to move the clutch operating member 99 into operative relation to the clutch dog 85.

For facilitating manual interruption of the feed of the web T, a hand lever 84 is pivoted as indicated at 88 and connected by means of a link 87 to the free end of an arm 88 which is pivoted as shown at 89 to the frame work of the apparatus. The link 87 underlies an end portion of the shaft (or a collar thereon) of the upper feed roller 58 and is adapted, upon rocking of the lever 84 in a clockwise direction, to raise the feed roller 58 so as to space it from the driven feed roller 59 to thereby disable the feed of the web. The link 87 is connected by means of a link 90 to an extension 81 of the lever 84 so as to also effect disengagement of the feeding roller 66 from the feed roller 67 when the feed roller 58 is disengaged from the feed roller 59.

The above described feed disabling mechanism is, of course, provided at both ends of the feed roller pairs, the mechanism at both sides being interconnected through the agency of the shaft 86 which is the pivot axis for the hand lever 84.

By reference to the Figure 36 it will be seen that the wrapper web T is notched out as indicated at 104 along one edge so as to leave projecting lips 105. Such notching is effected by means of a punch 104a carried by the cross-lead brackets 76a (Figure 3) and a die opening 104b (Figure 5) formed in a margin of the die plate 71. The lips 105 extend across the width at the top edge of the package to be formed. In Figure 36 the broken line 106 indicates the line along which the web is severed by the shearing blades 73 and 75 so as to form a separated wrapper member W. The embossing dies 71-80 serve to emboss or crease the wrapper W along the various lines indicated in Figure 36, the said dies being operative to crease that portion of the web located between the broken lines designated 107 on Figure 36.

The package or receptacle forming, filling and closing mechanism is carried by a rotating, cage-like structure which comprises upper and lower spiders 122 and 123, respectively, and a plurality of circumferentially spaced posts 121. The upper and lower spiders 122 and 123, respectively, are each provided with suitable hubs adapted to rotatably fit on the central post 52 and an anti-friction thrust bearing 128 is interposed between the lower spider 123 and the supporting hub 129 of the lower stationary frame member 51. A suitable anti-friction sleeve or bushing 130 may be provided for rotatably supporting the upper spider 122 on said post 52. The posts 121 are spaced circumferentially around the spiders 122 and 123 and serve to maintain the latter in fixed spaced relation.

The described cage-like structure is continuously rotated by a driving connection with the continuously driven shaft 62. Said driving connection comprises a suitably journaled shaft 131, beveled gearing indicated at 132 for connecting the shaft 131 to the shaft 62 and a beveled gear 133 on the shaft 131, and a ring gear 134 meshing with said beveled gear 133 and carried by the bottom side of the lower spider 123.

The wrappers W which are successively cut from the web are adapted to be successively received by carriers or baskets, carried by the 75

above described cage structure. Said carriers comprise a bottom member 110 (Figures 5, 7, 8, 9, 23, 24, 25, 28, and 31) which is a frame-like device equipped with a forward extension 111, a rearwardly extending leg 112 and a mounting ear 113. Said ear 113 is provided on its lower side with a boss 114. The boss 114 has a reduced diameter extension 115 which is adapted to be suitably journaled in a member 116 which is in turn mounted in the upper leg 117 of a bracket 118.

The bracket 118 has a lower leg portion 118 and a pair of depending elongated bosses 120 and said bracket is rigidly mounted on the vertically extending posts 121-121 of the rotating cage structure.

As indicated in Figure 7 the upper leg 117 of each bracket 118 is provided with ears 123 and 124 at its opposite sides and the lower leg 118 is similarly equipped with ears 125 and 126. Said ears are adapted to be disposed against the respectively adjacent posts 121 and, as shown, said ears are so shaped and notched as to embrace substantially one-half the circumference of attaching bolts 127 which serve to secure said ears to the respective posts 121. As best indicated in Figure 7 each bolt 127 is embraced by the adjacent ears of adjacent frame members 118 and it will be evident that said brackets 118 constitute, in effect, a continuous frame-like structure carried by and extending around the cage-like structure.

The member 110 is further rotatably supported by the lower end portion of a shaft 135 which is extended as indicated at 135-A through the reduced diameter boss 115 so as to be itself supported in the member 117. The upper end of the shaft 135 is connected by means of a coupling 136 to a shaft member 137. The shaft 137 is journaled in a boss 138 of a bracket 139 and the upper end portion of said shaft 137 is provided with gear teeth as indicated at 140. The provision of the coupling-connection between the shaft 135 and the shaft 137 facilitates assembling operations and also permits accurate adjustment to be made between the shafts 135 and 137, the latter being of substantial importance to secure proper positioning of the wrapper carriers.

The bottom member 110 slidably supports a tray 141 which is equipped with upstanding flanges 142 adapted to position a wrapper on the tray. At one side said tray is provided with a rack bar 143.

Another basket member 144 of channel shaped cross-section is assembled with said members 110 and 141 so that the channel shaped portion of the member 144 houses the rack bar 143. The member 144 is provided with an upwardly extended hub 145 which rotatably fits on the shaft 135 so that said members 144, 141 and 110 are adapted to be rotated as a unit about said shaft 135. The member 144 is provided with a pair of upstanding ears 146-146 which are adapted to receive adjustable stop screws 147-147 (Figure 28) for engaging the adjacent post 121 to limit the extent of movement of the said basket structure about said shaft 135.

The shaft 135 is actuated by means of a rack bar 148 which is slidably mounted in the bracket 139 and which meshes with the gear teeth 140 at the upper end of said shaft 135. Said rack bar 148 extends inwardly and at its inner end is provided with a cam following roller 149 which is adapted to engage a cam 150.

The cam 150 extends inwardly from a cylin-

drical supporting member 151 which is carried in fixed position by a spider 152. Said spider 152 is fixed on said post 52 so as to be stationary whereby said cam 150 is in turn supported in a fixed position. As indicated in Figure 22, there is associated with said cam 150 an auxiliary cam 153, the latter being supported by suitable bracket connections to the cam 150, said member 153 cooperates with the outwardly receding portions of the cam 150 to form a positive guide for acting on the cam following rollers 149 to insure outward movement of the rock bars 148 when required.

The wrapper receiving and advancing basket structures are continuously advanced as incident to the continuous rotation of the cage structure comprising the upper and lower spiders 122 and 123 and the posts 121. The wrapper members W are fed to the machine in a direction extending transversely of the direction of movement of the baskets; hence, it is desirable that provision be made for temporarily stopping the movement of the wrapper receiving trays 141 while the wrappers are being delivered thereto. Such stopping of the trays is effected by so operating the mechanism as to cause the tray 141 to be located in its position of greatest advancement relative to the underlying frame member 110 and then, when the tray reaches wrapper receiving position, stopping the travel of the tray while permitting continued movement of the underlying supporting member 110. As shown in Figure 22, the tray 141 of the basket designated A is in advanced relation to the frame member 110. When the tray 141 of said basket A reaches the wrapper receiving position of the basket marked B, a sharply inwardly inclined portion 154 of the cam 150 effects inward movement of the rock bar 148 to thereby effect counter clockwise movement of the shaft 135. The lower end of the shaft 135, within said member 144 is equipped with a pinion gear 155 which meshes with the rack bar 143 of the tray 141. Hence counter clockwise rotation of the shaft 135 effects rearward movement of the tray 141 relative to the frame 110, or conversely, forward movement of the frame 110 relative to the tray 141. Hence, there is effected a period of rest of the tray 141 when in the wrapper receiving position without interrupting the continued movement of the frame 110 and other basket parts.

To facilitate delivery of the wrappers to the respective trays, the wrapper feeding and cutting mechanism is so timed that it is at least advisable to provide means for preventing the rear edge of the wrapper from sagging into the path of movement of the basket. Such means comprises a supporting member 156 which is carried by the lower end of an arm 157, the latter being pivoted at its upper end as indicated at 158 (Figures 3 and 6) in a fixed bracket 159. The upper end of said arm 157 has a forwardly extending arm 160 which slidably receives a rod 161, the lower end of which is secured to a strap 162 projecting from the crosshead 76. When the crosshead 76 reaches its lower-most position, suitable stop means 163 on the rod 161 will engage the arm 160 so as to rock the member 157 and its supporting element 156 rearwardly so as to thereby permit any overlying portion of a wrapper member to drop into the underlying tray 141.

As best shown in Figure 22, the present mechanism comprises a series of 10 of the above de-

scribed wrapper carrying basket devices. For purposes of simplifying the operating structure required for forming the wrappers into receptacles, it is preferred that the wrappers be turned through an angle of 90° from the position in which they are delivered to the respective baskets. For this purpose, each basket, after receiving a wrapper is turned through an angle of 90° so as to present said wrapper in the most advantageous position for subsequent operations. Such turning movement is effected by so shaping the cam 150 as to continue the inward movement of the rack bars 148 at a relatively slow pace as indicated in Figure 22; the turning of the baskets through an angle of 90° occupies about one-fourth of the travel of the baskets around the circumference of the machine. The turning movement of each basket begins after its tray 141 has been retracted or caused to assume a normal position relative to its underlying supporting frame 110. Said normal position is determined by engagement of the rear end 163 of the rack bar 143 with an adjustable stop 164 carried by the housing member 144. Counterclockwise rotation of the shaft 135 is, after engagement of said rack bar end and stop 164, effective to cause counter-clockwise turning of the respective baskets about the axis of the shaft 135.

A coil spring 165 disposed about the shaft 135 has one end anchored to said shaft as indicated at 166 and its other end extended to engage the adjacent post 121. The counter-clockwise rotation of said shaft 135 tensions said spring 165 so that when the cam 150 permits the rack bars 148 to move inwardly, said shaft will be rotated in a clockwise direction so as to cause the cam-following rollers 149 to normally follow the receding portion of the cam.

Another coil spring 167 is disposed about the hub 145 of the housing member 144, one end of said spring being anchored to said housing member and the other end being arranged to engage the adjacent post 121. Said spring 167 is so arranged as to normally resist counter-clockwise turning movement of the basket structure about the axis of the shaft 135 but permits such movement when the tray 141 is fully retracted. In other words, the spring 167 serves to prevent turning of the basket merely as an incident to the frictional driving force which exists between the tray and the underlying frame member 110. Said spring 167 also serves to restore the baskets to their wrapper-receiving position when permitted to do so by the cam 150.

An air pipe P may be provided and arranged with a discharge slit or openings to direct a current of air downwardly against the wrappers carried by said baskets, thereby to hold the wrappers in place until they are mechanically held incident to subsequent operations of the mechanism.

There is associated with each of the wrapper-carrying baskets, means for forming the wrapper carried by the basket into a receptacle, filling the receptacle and then closing and sealing the same. The forming mechanism comprises a hollow or tubular mandrel 168 which depends from a vertically slidably mounted bracket. The bracket 169 is vertically slidably mounted on a square post 170 which is supported at its upper end by attachment to the upper rotating spider member 122 and at its lower end by attachment to an inwardly projecting portion of the bracket 118. Adjacent its inner end, the bracket

168 carries a roller 171 which engages a cam 172 carried by said stationary cylinder 151. Co-operating with said cam 172 is another cam member 173 (see Figures 8, 9, 28, and 29) which is adapted to overly said roller 171 so as to insure downward movement of the mandrel when permitted by the underlying cam 172.

Said cam member 173 is carried by the outer end of an arm 174 which is mounted on the stationary central post 52 (Figure 4). Said arm 174 is normally retained against rotation about the post 52 by means of a spring pressed plunger 175 carried by the arm and normally projecting upwardly into engagement with a latch member 176 which is rigidly secured to the stationary cylindrical member 151. In the event that a downward movement of the mandrel 168 is prevented, the engagement of the cam following roller 171 with the cam 173 will force said arm 174 to turn on the supporting shaft 52, automatically effecting disengagement of the spring pressed plunger 175 from the latch 176. As an incident to such movement of the arm 174 an adjustable stop 177 carried thereby permits a plunger member 178 to move outwardly to operate a suitable electric switch 179 to thereby open the circuit to the driving motor 65, whereby the operation of the machine is stopped so as to prevent damage to any of its parts incident to the existence of such obstruction or other element which prevented normal downward movement of the mandrel 168.

The initial position of the hollow mandrel 168 is substantially as shown in Figure 7 wherein the lower end of the mandrel is spaced upwardly from the wrapper carrying tray. After the wrapper tray has been turned through an angle of 90° so as to properly position the wrapper carried thereon with reference to the mandrel, the latter is lowered. In the downward movement of the mandrel 168, it first engages the wrapper W (see Figure 9) and forces the same downwardly through the central opening 180 in the tray 141 and between a pair of rollers 181 and 182 which are carried by the basket member 110. Each of the rollers 181 and 182 is mounted for sliding movement transversely of the mandrel and normally urged to move inwardly by spring means so that the said rollers operate to fold the wrapper member W around the mandrel 168. As shown in Figure 9 the wrapper is initially folded into U form providing a bottom portion W-1 and front and back sides W-2 and W-3 respectively. The first operation of the plunger is then to shape the wrapper blank into the form illustrated in Figure 37.

Each roller 181 and 182 is rotatably mounted in suitable ears formed as a part of a bracket member 183 (see Figures 9 and 32) and each bracket member is suitably slotted as indicated at 184 to receive guide members 185 which may be in the form of screws and which screws serve to secure a plate 186 to the member 110 for supporting the bracket member 183. The bracket member 183 is provided with suitable ear extensions such as indicated at 187 and the plate 186 with similar extensions 188 which extensions serve to position coil springs 189. The coil springs 189 are such as to normally urge the roller 181 or 182 to move inwardly towards the mandrel. Such spring effected movement is, however, limited by means such as ears 190 formed on the slideable member 183 for engagement with portions of the supporting plate 186 for the purpose of releasing the mandrel 168 from unnecessary

strains, incident to the inward pressure exerted by the rollers 181 and 182. The mandrel is reinforced at its ends by means of relatively stout strap members designated at 195 and 196. Said strap members are adapted to engage the enlarged portions of the rollers 181 and 182 as clearly shown in Figure 32. Another important benefit obtained from the arrangement of enlarged end portions on the rollers is that the wrapper is not subjected to any substantial surface contact with the rollers so that any tendency to impair printed matter or to tear or otherwise damage the wrapper is largely eliminated.

The mandrel 168 carries the wrapper downwardly sufficiently to clear the rollers 181 and 182 and until the bottom forming portion W-1 of the wrapper is disposed on the top of the upper portion 117 of the bracket 118. Said bracket 118 has pivotally mounted on it, inner and outer plates 191 and 192 respectively, the same being pivoted on the bracket part 117 as indicated at 193 and 194 respectively. Said plates 191 and 192 are normally maintained in their approximately vertical position as shown in Figure 9. They embrace the U shaped wrapper but receive the same freely therebetween.

Said bracket portion 117 also has pivotally mounted on it a pair of rock members 197-198. Said members 197-198 slidably support plates designated 199, each of which plates has its upper and outer end portion 200 pointed as mostly clearly shown in Figure 16. The plates 199 are slidably mounted on the members 197 and 198 by being longitudinally slotted as shown at 201 and fitted over guide projections 202 formed integrally with the members 197-198 respectively. Plates 203 seated on said guide members 202 and suitably secured thereto by screws as shown serve to retain the plates 199 in operative position on the members 197 and 198. The lower or inner ends of said plates are connected together by means of a coil spring 204 which normally tends to hold said plates in their initial positions as shown in Figure 13 wherein the members 197 and 198 engage suitable stop lugs indicated at 205 formed integrally with a bracket part 117.

The members 197 and 198 are mounted in the bracket part 117 for rocking movement through the agency of suitable shafts 206 and 207 respectively which have their inner ends offset so as to form crank arms 208 and 209 respectively. Said crank arms 208 and 209 constitute, in effect, cam followers and are adapted to be engaged and be actuated by cams 210 and 211 respectively which are carried by a disc 212. The disc 212 is supported in fixed stationary position by being secured to a drum-like member 213 which is suitably mounted on the fixed central post 52 (see Figure 4).

When the wrapper W is moved downwardly to form it into U shape, the opposite end portions of the bottom part W-1 engage the pointed end portions 200 of the plates 199 and are thereby offset upwardly in the form of an inverted V as shown at V in Figures 16 and 37. Incident to such shaping of the bottom portions, the corresponding portions of the front and back wall parts of the wrapper are also offset inwardly as indicated in Figure 37.

The mandrel carrying bracket 169 is equipped with a pair of ears 214 from which are suspended pairs of downwardly and outwardly diverging spring elements 215. The lower ends of said diverging spring elements 215 are adapted to engage the end portions of the wrapper approx-

imately in the corner formed between the bottom part W—1 thereof and the respective side wall parts and serve to resist upward displacement of the corner portions of the wrapper, incident to the formation of said inverted V shape in said bottom portions.

After the wrapper has been formed to the condition illustrated in Figures 13, 16, and 37 the members 197 and 198 are caused, by proper formations on the cams 210 and 211, to be rocked in opposite directions so as to cause the pointed end portions 200 of the plates 199 to fold triangular portions of the bottom wall W—1 of the wrapper into upwardly extending position against the outside walls of the mandrel reinforcing parts 195 and 196 (Figure 14). Incident to such further forming of the bottom wall the corresponding end portions of the wrapper walls are brought together to a somewhat greater extent as indicated in Figure 38.

The end portions W—4 and W—5 of the front and back walls of the wrapper are next pressed into contact with each other and sealed together. The means for accomplishing such side sealing comprises a pair of sealing elements or bars 216 and 216—A and another pair of similar elements 217 and 217—A. The sealer elements or bars 216 and 217 embody electrical heating units 218 and the said bars are carried by the free ends of forked arms 219 and 220 respectively. The arm 219 has a hub portion 219—A secured to the upper end portion of a sleeve 222 which is rotatably positioned on a shaft 221. The shaft 221 is journaled adjacent its upper end in a suitable bearing opening in the upper bracket portion 117, and the sleeve 222 is journaled in the elongated boss 120 of the lower bracket portion 119. The lower end of said sleeve 222 is equipped with an arm 223 which is connected by means of a link 224 to an arm 225. The arm 225 is mounted on the lower end portion of a sleeve 226 which is positioned on a shaft 227. The shaft 227, like the shaft 221, is journaled adjacent its upper end in the upper bracket portion 117 and the sleeve 226, like the sleeve 222, is journaled in the depending boss 120 of the lower bracket portion 119. Said arm 225 is provided with an extension 228 and with a spring extension 229 which carries a roller 230 at its outer end. The roller 230 is adapted to engage a cam 231 carried by the stationary drum element 213.

When the roller 230 engages the cam 231, the arms 228 and 225 together with the sleeve 226 are rocked in a clockwise direction and the arm 223 and sleeve 222 are similarly rocked in a clockwise direction. Accordingly the electrically heated sealing bar 216 which is carried by the arm 219 will be moved inwardly. The sealing bar 216—A which cooperates with the sealing bar 216 is carried by a forked arm 232 which has a hub portion 232—A secured to the shaft 221. The lower end portion of said shaft 221 is provided with an arm 233 which is connected by means of a link 234 to the arm 228. Hence it will be seen that when the arm 228 is rocked in a clockwise direction, the arm 223 and shaft 221 will be rocked in a counter clockwise direction. Thus the sealing bar 216—A will also be advanced in a counter clockwise direction so as to meet and cooperate with the sealing bar 216.

The arm 233 is also connected by means of a link 235 to an arm 236 which is secured to the lower end of the shaft 226.

The forked arm 220 which carries the sealing bar 217 has a hub portion 220—A secured to the

shaft 221. When the shaft 221 is rocked in a counter clockwise direction, incident to its connection by means of the arm 236, link 235 and arm 233, the said sealing bar 217 will be advanced in a counter clockwise direction. The sealing bar 217—A is carried by a suitably forked arm 237 which has a hub portion 237—A mounted on the upper end of the sleeve 226. Said sleeve 226 is normally turned in a clockwise direction, incident to the cam action against the arm 228 which is carried by said sleeve 226. Hence the sealing bar 217—A will be advanced in a clockwise direction so as to meet and cooperate with the electrically heated sealing bar 217.

The arms 233 and 236 are interconnected by means of a coil spring 238 which normally holds the sealing bars in their open position as shown in Figures 7, 12, 33 and 35. The cam 231 is so shaped (Figure 26) as to maintain said sealer bars in their closed sealing position for such length of time as is found necessary to effect satisfactory sealing of the packages, such time interval being somewhat dependent upon the kind of coating or cement employed on the wrapper sheets.

For controlling opening of the sealing devices there are provided cams 239 and 239a. During the course of travel of the package forming structure about the axis of the central post 52, a roller 240 carried by an extended portion of the arm 225 will engage said cam 239 (Figure 26) so as to control the opening action produced by the spring 239. In order to avoid severe action, the opening of the sealer bars is effected in two stages, wherefore the cam 231 is provided with an extension 231—A for temporarily holding the sealer bars in partly closed or partly opened position. The cam 239a is arranged to act on the roller 240 so as to cooperate with the end of the cam part 231—A for preventing violent action in the sealer bar mechanism in its final opening movement.

The filling of the receptacle formed as above described is preferably effected while the sealer bars are in closed position, this being permissible especially in view of the fact that the sealer bars are spaced from the inside of the bag, not only by the thickness of the wrapping material but also by the thickness of the mandrel 168 and its side reinforcements 195 and 196. Accordingly, while the mandrel 168 is in its lowered position as shown in Figure 9, the material to be packaged is delivered into said mandrel. By delivering the material into the mandrel while the latter is within the receptacle, the latter is protected against distortion or other injury due to the deposition of the material in the bag.

In the present apparatus, the material to be packaged is of a grated, granular or powdery nature, and a supply thereof is initially deposited in a circular tray 241, (Figures 1, 4 and 9). The tray 241 is equipped with a central boss 242 which fits slidably on a shaft element 243 which is suitably mounted as shown in Figure 4 on the hub of the upper spider 122 which rotates continuously. The tray is supported in a vertically adjusted position by means of a member 244 which is rotatably supported on the upper end of the shaft 243. Said member 244 is provided with a screw threaded extension 245 which engages a correspondingly threaded portion of the hub 242. The upper end of the member 244 may be provided with a hand wheel 246 for facilitating rotation of the member 244 to thereby effect vertical adjustment of the tray 241 on the post 243.

The tray 241 is caused to rotate in unison with the rotating cage structure by means of a vertically adjustable connection to the upper spider 122. Such connection is best shown in Figure 9 and comprises a post 247 rigidly secured to a depending boss from the tray 241 and slidably entering an opening in a bracket 248 carried by said spider 122.

The tray 241 is provided with a series of downwardly extending spouts 249, one for each package forming station and mandrel 168 and each spout 249 enters a sleeve 250. The sleeve 250 rests on a valve plate 251 which is carried by an oval shaped frame 252, the latter having an inwardly extending arm 253 which is pivoted as indicated at 254 on bracket member 255. The bracket 255 is suitably secured to the spider 122 and provides a smooth upper edge surface 256 on which the frame 252 is adapted to slide.

The plate 251 is provided with an opening 257, adjacent one end of the oval frame. Said plate 251 serves to close the bottom of the sleeve 250 so as to prevent the passage therethrough of material from the tray 241 and the opening 257 in said plate constitutes a valve opening for permitting passage of the material when the frame is shifted to align said opening with said sleeve.

For shifting the oval frame 252 and valve plate 251, the said frame is provided with a roller 258 carried by a short arm extension of the frame. Said roller is adapted to engage the end 259 of a normally stationary cam 260 whereby the members 251 and 252 will be shifted to effect alignment of the valve opening 257 with the sleeve 250. A tension spring 254a, suitably arranged on the pivot pin 254 and connected to the shiftable frame 252 and the relatively stationary bracket member 255, yieldingly resists opening of the valve and serves to close the same when permitted to do so by the cam 260.

The cam 260 is mounted on the upper end of an arm 261 (Figure 4) which is pivoted at its lower end as shown at 262 in a bracket 263 carried by an arm extending upwardly from one of the legs of the machine. A spring 264 interposed between the arm 261 and the bracket 263 normally maintains the cam 260 in predetermined inwardly disposed position as determined by a limiting bolt 265 but permits said cam to be forced outwardly in the event that the valve mechanism 251 and 252 is locked against shifting.

The valve structure 251-252 is automatically locked against opening by means of a locking pin 266 carried by one end of a lever 267. Said locking pin 266 is slidably supported in a suitable opening 268 provided in a portion of the bracket structure 255 and said pin is adapted to enter a suitable opening 269 provided in a part of the valve frame 252 (Figure 12).

The lever 267 is pivoted intermediate its ends as shown at 270 on the side of the bracket structure 255 and the opposite end of said lever is connected by means of a link 271 to an arm 272. The arm 272 is pivoted intermediate its ends as indicated at 273 and has a free end portion arranged to support a pin 274 which is slidable vertically through the bracket part 117 which forms the support for the bottom W-1 of the wrapper (Figures 7, 9, 12, 15 and 33). The upper end of said pin 274 carries a crossbar 275 which, in the absence of a wrapper portion W-1 across the bottom of the mandrel 168 will be disposed above the surface of the bracket part 117 as shown in Figures 7 and 12.

Movement of the locking pin 266 into locking

position, and incidentally the elevation of the feeler member 275 to the position shown in Figures 7 and 12 is effected by means of an upwardly extending arm 276 (Figure 12) which is connected to the mandrel supporting bracket 169. At an appropriate point as indicated at 277 (Figure 29), the cam 172 is provided with a rise which is sufficient to move the bracket member 169 and member 276 upwardly to an extent sufficient to adjust the locking pin 266 into locking position.

The arm 267, and the locking pin 266 and feeler or detector member 275, is frictionally maintained in adjusted position by means of a coil spring 278 disposed about the pivot pin 270 of the lever 267. Said spring 278 acts to press a friction washer 279 against the adjacent portion of the arm 267 so as to frictionally resist rocking of said lever. The friction washer 278 is anchored against rotation by any suitable means, for example, as shown in Figures 7 and 12.

When the receptacle is formed about the lower end of the mandrel 168, the bottom portion W-1 of such wrapper engages the detector member 275 and forces the same downwardly until its upper surface is flush with the upper surface of the bracket part 117 which supports said wrapper portion. Such downward movement of the detector member is of course transmitted through the lever 272, the link 271, and the lever 267 to the locking pin 266 to withdraw the same so as to unlock the valve mechanism for operation by the cam 260 as already explained. In the event that a wrapper is missing from a given mandrel 168, the locking pin 266 will not be disengaged and hence the valve structure will remain locked to prevent opening of the valve and delivery of material to the mandrel from which the wrapper is missing.

For the purpose of delivering the material to be packaged to the spouts 249 and sleeves 250 there is provided within the tray suitable devices for agitating and distributing the material. Such devices may be of any suitable form but in this instance they comprise (Figures 1 and 4) a member 280 carried by an arm 281 which is secured to a bracket 282. The bracket 282 is secured to a bracket structure 283 which is supported by being connected to the stationary post 57. The member 281 is arranged to guide material towards the side wall of the tray and over and into the spouts 249. Another member 284 is arranged with its bottom edge 285 spaced upwardly from the bottom of the tray 241 and at an inwardly inclined angle so as to plow inwardly some of the material from adjacent the side wall of the tray. A vertically adjustable plate 286 may be provided on a part of the member 284 for similarly plowing the material from a position outwardly adjacent the hub of the tray.

Another member 287 supported by an arm 288 is arranged to return some of the material to a position adjacent the outside wall of the tray to thereby, for a second time, deliver material to the spouts 249.

Another plow-like device 289 is arranged with its bottom edge in contact with or closely adjacent the bottom of the tray 241 and so as to plow the material inwardly from adjacent said side wall. Said member 289 is desirably maintained in a substantially vertical or other predetermined angular relation to the bottom of the tray 241 so that it will always produce the same packing effect on the material delivered to the

spouts 249. In this instance said member 289 is carried by an arrangement of parallel links 290 which are connected to the bracket structure 283.

For the purpose of facilitating vertical adjustment of the various plow-like devices to correspond with any vertical adjustment of the tray, the bracket structure 283 which carries all of said plow devices is mounted on said posts 57 so as to be vertically slideable thereon. An adjusting screw 291 (Figures 1 and 3) is carried by a portion of the bracket structure 283 and is adapted to engage a normally stationary transverse member 292 which is secured to said posts 57. By turning the screw 291, the bracket structure 283 and the plow devices carried thereby may be raised or lowered as may be required.

It will be observed that the spouts 249 and their complementary sleeves 250 constitute, in effect, measuring cups and that said measuring cups are simultaneously adjustable as to capacity by vertical adjustment of the tray 241. This follows from the fact that the spouts 249 fit slidably in the sleeves 250 which rest on the valve plates 251.

The material to be packaged (for example, grated cheese, gelatin powder or other comminuted material) falls by gravity into a funnel 168a which is fixedly carried by the rotating cage structure, thence into a fixedly mounted conduit 168b which fits telescopically into the vertically movable, hollow mandrel 168 which, in turn, delivers the material to the container formed on the lower end thereof.

After the packages or containers are filled with the desired quantity of material, the mandrel 168 is withdrawn by being moved upwardly. Such action is effected by a rise indicated at 172—A (Figure 29) in the cam 172. Thereafter, the end walls of the package are tucked inwardly near the top of the container so as to facilitate closing of the package by bringing the upper portions of the sidewalls W—2 and W—3 of the package in face-to-face contact. For so tucking the end walls of the container there is provided for each package-forming structure a pair of tucking members comprising arms 292 and 293 which are mounted on shafts 294 and 295, respectively, the latter being rotatably mounted in the bracket part 119. The upper ends of said arms 292 and 293 are provided with elongated head portions 292—A and 293—A, respectively, which are adapted to engage the end walls of the receptacle as best shown in Figure 18. As there shown, the members 292—A and 293—A engage the united marginal portions of the wrapper, thereby acting against a reinforced portion of the receptacle, to press said end walls inwardly along predetermined lines on which the wrapper was preliminarily creased for such folding action.

As shown in Figures 17 and 18, the transversely arcuate form of the united marginal portions of the wrapper is produced by the correspondingly shaped sealer bars, such form being somewhat advantageous for the indicated action of the tucking members 292 and 293. The tucking members 292 and 293 are provided with depending arm portions 292—B and 293—B, respectively, which are connected to each other by means of a coil spring 296 which normally urges the head portions 292—A and 293—A to move outwardly to their normal position as shown in Figure 14. The inward or tucking movement of the members 292 and 293 is ef-

fected by means of cams 297 and 298 (Figures 4 and 26) which are carried by the stationary disc 212. Said cams engage crank arm extensions 294—A and 295—A of the tucker arm shafts 294 and 295 respectively.

When the cams 297 and 298 permit the spring 296 to restore the tucker arms 292 and 293 to normal position, the pointed end plate members 199 are retracted by means of cam arms 292—C and 293—C which are formed integral with said tucking members. The said cam arms slide through suitable slots in the lower ends of the plates 199 and the free ends of said cam arms are provided with stop shoulders 299 which serve to prevent escape of said cam arms from the openings in the plates 199. The cams 297 and 298 which control the rocking movement of the tucker arms 292 and 293 are so designed as to impart only the required amount of inward movement to the upper ends 292—A and 293—A of said tucker arms which should not ordinarily cause the cam arms to be withdrawn from the slots in said plates 199. The shoulder provision serves however to prevent excess movement of the tucker members as a result of inertia or from other causes.

The pointed plates 199 are restored to their initial positions as shown in Figure 13 when the cams 297 and 298 permit the spring 296 to disengage the tuckers from the receptacle. When the tucking members are moved outwardly by said spring 296, the cam arms 292—C and 293—C serve, incident to their inward movement, to adjust the plates 199 outwardly to their initial positions. In a similar manner, the members 197 and 198 are restored by the spring 204 to their initial inclined positions, i. e., when the cams 210 and 211 permit the spring to function.

The side walls W—2 and W—3 of the container are brought together in face to face relation adjacent their upper ends as indicated in Figure 41 by rocking the plates 191 and 192 inwardly on their respective pivots 193 and 194. Such inward movement of the plate 191 is effected by means of a cam 300 (Figures 16, 19, 20 and 26) which is carried by the disc 212. Said cam operates against a roller 301 carried by an arm 302 which is pivotally connected as shown at 303 to a sealer bar head 304 which is carried by the free end of the plate 191. Said sealer bar 304 contains an electrical heating element 305 and it is thermally insulated as indicated at 306 from the plate 191. The arm 302 carries an extension which is adapted to perform a sealing operation presently to be described and said arm is connected by means of a spring 308 to the bracket portion 117. The portion of the cam 300 first engaged by the roller 301 is so shaped as to effect sufficient upward movement of the arm 302 to rock the plate 191 inwardly to the extent indicated in the drawings. The inward movement may conveniently be limited by means of an adjustable stop member 309 carried by a flange-like portion of the plate 191 and adapted to engage the bracket part 117. Similarly the outer position of the plate 191 may be determined by an adjustable stop member 310 which is also adapted to engage a portion of said bracket part 117.

The plate 192 is caused to move inwardly from its initial position as shown in Figure 9 to the position shown in Figure 19 by means of a cam 311 (see Figures 19, 20 and 26). Said cam 311 is carried by a flange 312 which is suitably

mounted (see Figure 4) on the upper ends of the legs of the stationary frame structure.

Said cam 311 is engaged by a roller 313 which is carried by a member 314 which is pivoted on the shaft 194 on which the plate 192 is also pivoted. The member 314 is equipped with a pair of sockets such as indicated at 315 for housing coil springs such as 316 through which inward movement of said member 314 effected by the cam 311 is transmitted to the plate 192. A coil spring 317 disposed about the shaft 194 is arranged with its opposite ends in engagement with the inside of the member 314 and a portion of the bracket part 117, so as to yieldingly resist inward movement of the member 314.

The cam 311 initially effects inward movement of the member 314 and the plate 192 simultaneously, the latter retaining their divergent relationship as shown in Figure 9. The plate 192 is formed with a suitable shoulder 318 which is adapted to engage an adjacent face portion of the bracket part 117 to limit inward movement of the plate 192. When the limit of inward movement of the plate 192 is reached, the inward movement of the member 314 is continued for a short distance by a portion 311a of the cam 311 which causes the member 314 to move inwardly and to incidentally compress the spring 316. As an incident to the inward movement of the member 314, a lip 319 provided at its upper end engages the upper marginal portion W6 which then comprises the marginal portions of both front and back sides of the container, and folds said marginal portion over the top surface 320 of the electrically heated sealing bar 304 (see Figure 19). The cam portion 311a is so shaped that the member 314 and its lip 319 are maintained in the extreme inner position only momentarily.

Just prior to the time the lip 319 is retracted, 40 the pivoted sealing member 307 carried by the other side plate 191 is caused to rock on its pivot 303 so as to fold the then upstanding lip part 105 of the wrapper downwardly toward the folded portion W6 of the wrapper. As the downward movement of the member 307 progresses, the lip 319 is permitted to be retracted under the force 45 of the spring 316 and the recession of the cam part 311a, and the wrapper lip 105 is ultimately squeezed tightly against the wrapper parts W6 which are then disposed on the adjacent surface 50 of the heated sealer bar 304. The cam 300 is so shaped as to actuate the sealing member 307 to apply the desired pressure against the folded marginal portion of the container so as to produce a strong seal between the respective parts 55 of the container.

When the top of the bag has been held under the sealing heat and pressure for the desired length of time, the cam 300 recedes so as to permit the roller 301 and arm 302 to swing downwardly so as to permit the spring 308 to restore the members 307 and 191 to their initial position as shown in Figures 9 and 12. The open position of the member 191 is limited by engagement 60 of its stop member 310 with a portion of the bracket part 117 and the open position of the member 307 is determined by engagement of a suitable stop member 321 with a portion of the member 191.

While the members 307 and 191 are being restored to initial position, the member 192 is being swung outwardly and downwardly to a horizontal position as shown in Figure 12, the same being accomplished by the spring 317 which 75

acts against the member 314. The outward and downward movement of the member 314 is transmitted to the plate 192 by means of a hook-like lug 322 carried by the plate and provided with an adjustable stop member 323 for engaging the outside of the member 314. The cam 311 is, of course, suitably shaped to permit such outward movement of the parts 314 and 192 and includes a part 311b which is engaged by the roller 313 when the plate 192 is in its lowermost, approximately horizontal position.

During its outward movement, the member 192 engages ears 324 which extend upwardly from arms 325. The said arms 325 are pivotally mounted on the shaft 194 and extend inwardly across that portion of the frame part 117 which supports the bottom of the container between the plates 191 and 192. The arms 325 may advantageously be provided with flange portions 326 (see Figures 20 and 33) for engagement with the bottom of the filled container. Each of the arms 325 is also equipped with a cam formation 327 which engages a roller 328 carried by a spring 329, the latter being suitably secured as indicated at 330 to the frame part 117. The spring 329 is flexed downwardly so that it normally applies an upwardly directed force to said cam form 327.

By reference to Figures 12 and 20, it will be apparent that incident to the upward and outward swinging movement imparted to the arms 325 by engagement of the plate 192 with the ears 324, the cam form 327 will be caused to flex the spring downwardly until the high point of the cam reaches the roller 328 and dead center is passed, whereupon the spring 329 will act against the cam 327 to accelerate the swinging movement of the arms 325. The arrangement is such that the accelerated movement of the arms 325 is permitted to occur at about the time the plate 192 reaches its fully opened position as shown in Figure 12, with the result that said accelerating movement is in effect a snap action.

The quick throw thus imparted to the arms 325 causes the latter to throw out the filled and sealed packages, the latter being thrown clear of the mechanism and being thus delivered to a suitable conveyor or other receiving device. Thereafter, the cam 311 is caused to restore the part 192 to its normal, approximately vertical position and to incidentally effect restoration of the throw-out arms 325 to their normal position by substantially the reverse of the throw-out action just described. Thereupon, the bag-forming structure is again in condition for receiving and operating upon another wrapper.

Provision is made for locking the wrapper-carrying devices in their normal wrapper-receiving position, thereby to prevent premature turning of the same. For so locking the wrapper-carrying devices, the hub 114 of each frame 110 is shaped so as to provide an abutment face 344 which, when the wrapper-receiving structure including the frame 110 is in its normal receiving position, is engaged by the outer end of a slidably mounted locking rod 345 (see Figures 5 and 32). The inner end of said locking rod 345 carries a roller 346 which is adapted to engage a cam 347 (see also Figure 26). Said roller 346 is connected to said locking rod 345 through the agency of a recessed thimble 348 into which the rod 345 fits telescopically, and a spring 349 is disposed around said locking rod 345 and between the bottom of said thimble 348 and an enlarged portion 350 on the rod.

Another spring 351 is positioned between the

face of the bearing 352, which is a portion of the frame part 117, and suitable ears such as indicated at 353 formed on the roller-carrying portion of the thimble 348. As best shown in Figure 5, when the wrapper-receiving trays or baskets are in their operative receiving position, the outer end of the rod 345 engages said face 344 of the hub of the frame 110. Incident to the pressure of the spring 349, the rod 345 acts against the face 344 which is inclined in such a manner that the frame 110 is urged to rotate to the full limit permitted by one of the stop members 146. When the wrapper has been delivered to the tray and when the tray has been advanced to the position in which the turning movement thereof is initiated, the cam 347 recedes, thereby lightening the pressure of the spring 349 so that the normal force applied for turning the basket structure is sufficient to cause the locking rod 345 to be thrust inwardly, so as to assume the position substantially as shown in Figure 32.

As already indicated, the members 191 and 192 are initially disposed in spaced relation to the adjacent sides of a wrapper disposed therebetween and around the lowered mandrel. For the purpose of holding the bag structure firmly in place on the mandrel while the various forming operations are being effected, there are provided wrapper-engaging rollers 331 outwardly of each of the plates 191 and 192, said rollers being carried by arms such as indicated at 332 which may conveniently be mounted for rocking movement on the shafts 193 and 194. Said arms are urged to move inwardly so as to press the respective rollers 331 against the wrappers by means of suitable flat springs 333, the latter each having one end suitably anchored to the adjacent plate 191 or 192 and its other end suitably connected to the adjacent arm 332. Said arms 332 are each provided with portions, for example, as indicated at 334, which are adapted to be engaged by underlying portions of the plates 191 and 192 to limit inward movement of the rollers 331, and also to cause said rollers and the respective arms 332 to move outwardly in unison with the outward swinging movement of the respectively adjacent plates 191 and 192.

For the purpose of detecting faulty closing of the side-sealing bars 216, 216a, 217 and 217a, there is provided at a suitable location on the apparatus an electric switch 335 which is adapted to be operated by movement of an arm 336. In the event that the said sealer bars are not closed to the desired extent, the arm 225 and its roller 240 will be disposed in an abnormally extended position. In such an event, the roller 240 is adapted to engage the switch arm 336 to actuate the switch to set in operation a suitable relay or other device for interrupting the electric circuit to the main driving motor 65.

A further safety feature is provided connection with the restoration of the wrapper-carrying baskets from their wrapper-delivering position to their wrapper-receiving position. Such means comprises an electric switch 337 suitably mounted on a part of the frame of the mechanism, said switch being provided with an upstanding arm 338, which, if rocked, will either make or break an electric circuit for controlling a relay or other device which in turn will break the electric circuit to the driving motor 65. The upstanding arm 338 is so located that in the event that one of the baskets fails to return completely to its wrapper-receiving position, a forward and outward corner portion thereof will engage said arm

to rock the same to effect stopping of the mechanism.

In the wiring diagram shown in Figure 27 there is indicated what might be called a relay box 339 which may contain a so-called "time-delay" relay indicated at 343.

Said box may also contain a plurality of visual signal lights indicated at 340, said signal lights being included in predetermined circuits for the various heating elements. In this instance there are indicated three such signal lights and it is contemplated that the heating elements 305 of the top sealers be included in a single circuit with one pilot light, that the electrical elements of the outer side-sealing members be included in a second circuit with another pilot light, and that the electrical elements of the inner side-sealing units be included in a circuit with a 3rd pilot light. Obviously, however, the circuit may be arranged in any desirable manner and signal lights provided to indicate to any desired degree of exactness, the specific location of a burned-out or otherwise defective or inoperative heating element.

The circuits for the electrical heating elements are so connected to the time-delay relay switch 343 that in the event a heating element becomes inoperative, the relay 343 will first energize the solenoid 103 so as to disengage the clutch bar 95, thereby to stop the operation of the wrapper web-feeding mechanism. The relay switch 343 does not, however, immediately stop the operation of the package-forming and filling mechanism, but is so arranged as to permit continued operation thereof for a full cycle of the mechanism, so as to permit the completion and discharge of all packages which were in the apparatus at the time the electrical heating element became defective. When such cycle of operation is completed, the relay switch 343 operates further to break the circuit to the electric motor 65 to stop the entire machine. Various manual switches (not shown) may be provided for controlling the solenoid 103, the heating elements and the motor 65.

For transmitting electric current to the electrical elements on the rotating structure, there are provided a series of stationary brushes designated 341 which convey the current to a corresponding number of commutator rings 342 which are mounted on the bottom of the lower spider member 123 so as to be insulated from each other and from the machine itself. Suitable connections may then be made from the commutator rings 342 to the various electrically operated elements which travel with the rotating structure.

It will be observed that the wrapper-carrying members have an operative or work cycle beginning at the position A (Figure 22) and continuing for only slightly more than about one-quarter of its travel around the machine. The work cycle of the mandrel and package-forming and closing mechanism may be said to begin where the work cycle of the carrier ends and continues through almost the entire travel of the parts around the machine, the only idle time being that required for restoring the parts from the package-discharge condition shown in Figure 12 to initial package-forming position as shown in Figure 7.

The described apparatus embodies a plurality of like units, in the disclosed instance ten units of like structure, and it is adapted to operate continuously with little or no attention from an

attendant. The entire operation is wholly automatic and adequate provision is made for preventing delivery of the product to be packaged in the absence for any reason of a container, and effective means is provided for insuring delivery to the containers of uniform, measured amounts of whatever product is being packaged. The particular mechanism herein illustrated is adapted to produce what might be called a satchel-shaped package which measures about three and one-half inches in width, three inches in height and a thickness of one and one-quarter inches at the bottom of the package, tapering to a thin edge at the top. However, it will be apparent that the mechanism may be altered to produce packages of other sizes and shapes while utilizing some or all of the advantages of the structural arrangement shown.

Other changes may also be made in the described construction without departing from the spirit of the invention, the scope of which should be determined by reference to the following claims, the same being construed as broadly as possible, consistent with the state of the art.

I claim:

1. In apparatus of the class described the combination of a continuously traveling supporting means, receptacle-forming means carried by said supporting means, means for receiving and delivering receptacle blanks to said forming mechanism comprising a receiving tray connected to said continuously traveling supporting means, and means for temporarily stopping the travel of said receiving means to receive a blank while continuing the travel of said supporting means.

2. Apparatus according to claim 1 wherein said tray is turned to a predetermined extent after receiving said blank so as to deliver the latter to the forming mechanism in a predetermined turned position.

3. Apparatus according to claim 1 wherein said tray is mounted on said supporting means so as to be slideable thereon both forwardly and rearwardly relative to the direction of travel thereof, means for adjusting said tray to advanced, blank-receiving position, and means for temporarily interrupting the normal travel of said tray so as to temporarily hold the same in said blank-receiving position.

4. Apparatus according to claim 1 wherein said tray is mounted on said supporting means so as to be slideable thereon both forwardly and rearwardly relative to the direction of travel thereof, means for adjusting said tray to advanced, blank-receiving position, means for temporarily interrupting the normal travel of said tray so as to temporarily hold the same in said blank-receiving position, while continuing the normal travel of said supporting means, whereby the tray is, in effect, moved rearwardly to its initial, normal, operative relation to said supporting means, and means operative after such restoration of the tray to normal operative position for turning said tray to a predetermined extent so as to deliver the blank in a predetermined, turned position to the receptacle-forming mechanism.

5. Apparatus of the class described comprising a continuously traveling support, receptacle-forming means carried by said support, means for delivering receptacle blanks to said forming mechanism comprising a frame carried by said support, a tray slidably mounted on said frame, means for adjusting said tray forwardly on said

frame in the normal direction of travel of the latter with said support, said tray and frame being mounted on said support for simultaneous turning movement, an actuating member operatively connected to said tray and frame for initially effecting rearward movement of said tray relative to said frame while the forward movement of the frame continues, thereby to hold said tray in stationary position for receiving a blank, said actuating member being subsequently operative to effect turning of said frame and tray as a unit so as to cause said tray to deliver said blank in predetermined, turned position, to said receptacle-forming means.

6. In apparatus of the class described, the combination of a hollow mandrel, means for forming a receptacle about one end of said hollow mandrel, said hollow mandrel being adapted to permit material to be packaged to be delivered to the receptacle formed on said end of the mandrel, means for effecting withdrawal of the mandrel from the filled receptacle while the latter remains in said forming means, means for closing the receptacle, and means comprising a part of said receptacle-forming means for discharging the filled and closed receptacle from said forming means.

7. In apparatus of the class described, the combination of means for guiding a web of sheet material from which to form receptacle blanks, means for severing forward end portions from said web to form said blanks, means movable transversely of the normal direction of travel of the blanks delivered by said guiding and severing means for receiving and propelling said blanks, means for supporting a marginal portion of said blanks in elevated position to prevent said receiving means from engaging the edge of the supported margin of said blank, and means for effecting withdrawal of said marginal support so as to deposit said blank on said receiving means.

8. In apparatus of the class described, the combination of receptacle-forming means comprising a slidably mounted mandrel, cam means for effecting sliding movement of said mandrel in a predetermined direction, means connected with said mandrel for engaging said cam so as to effect operation of said mandrel, means for yieldably mounting said cam so as to permit displacement thereof incident to the engagement therewith of said cam-engaging means in the event that said movement of the mandrel is abnormally resisted, thereby to prevent injury to the mechanism.

9. In apparatus of the class described, the combination of receptacle-forming means comprising a slidably mounted mandrel, cam means for effecting sliding movement of said mandrel in a predetermined direction, means connected with said mandrel for engaging said cam so as to effect operation of said mandrel, means for yieldably mounting said cam so as to permit displacement thereof incident to the engagement therewith of said cam-engaging means in the event that said movement of the mandrel is abnormally recessed, and means actuated as an incident to such displacement of said cam for automatically stopping the travel of said cam for automatically stopping the travel of said mandrel and cam-engaging means.

10. In apparatus of the class described, the combination of receptacle-forming means comprising a yieldably mounted mandrel normally continuously driven in one direction, cam means for effecting sliding movement of said mandrel

in a predetermined direction, means connected with said mandrel for engaging said cam so as to effect operation of said mandrel, means for yieldably mounting said cam so as to permit displacement thereof incident to the engagement therewith of said cam-engaging means in the event that said movement of the mandrel is abnormally resisted, thereby to prevent injury to the mechanism.

11. In apparatus of the class described, the combination of receptacle-forming means, means for receiving and delivering receptacle blanks to said receptacle-forming means, said receiving means comprising a frame, means for rotatably mounting said frame, a tray mounted on said frame for sliding movement thereon, means for locking said frame against rotation from its normal receptacle blank-receiving position, means for effecting sliding movement of said tray forwardly relative to said frame, means for thereafter effecting forward movement of said frame relative to said tray, thereby to temporarily maintain the latter in substantially stationary position for receiving a wrapper blank, and means for unlocking said frame so as to permit the latter to be turned after the wrapper blank is deposited in said tray.

12. In apparatus of the class described, the combination of receptacle-forming means, means for receiving and delivering receptacle blanks to said receptacle-forming means, said receiving means comprising a frame, means for rotatably mounting said frame, means for locking said frame against rotation from its normal receptacle blank-receiving position, and means for unlocking said frame so as to permit the latter to be turned after the wrapper blank is deposited in said tray.

13. In apparatus of the class described, the combination of receptacle-forming means, means for receiving and delivering receptacle blanks to said receptacle-forming means, said receiving means comprising a frame, means for rotatably mounting said frame, a tray mounted on said frame for sliding movement thereon, means for locking said frame against rotation from its normal receptacle blank-receiving position, means comprising a rotatably driven shaft connected to said tray for effecting sliding movement of said tray to advanced position relative to said frame, means for reversely actuating said shaft so as to effect forward movement of said frame relative to said tray, thereby to maintain the tray in substantially stationary position for receiving a receptacle blank, and means whereby continued reversed rotation of said shaft is operative to effect turning movement of said frame and tray so as to deliver the receptacle blank to said receptacle-forming means in a predetermined turned position.

14. Apparatus according to claim 13 wherein means is provided for locking the receptacle blank-receiving mechanism against turning movement while in blank-receiving position.

15. In apparatus of the class described, receptacle-forming means comprising a mandrel, means adapted to initially fold a wrapper sheet transversely around the bottom and one pair of oppositely disposed sides of said mandrel, distending means spaced from another oppositely disposed pair of sides of said mandrel for cooperating with the latter to maintain marginal portions of the wrapper which extend beyond said other pair of sides in smoothly extending condition, and means adapted to engage said ex-

tending wrapper portions intermediate said cooperating means and said mandrel sides for folding said wrapper portions together so as to complete the formation of the wrapper into a receptacle.

16. In apparatus of the class described, receptacle-forming means comprising a mandrel, means adapted to initially fold a wrapper sheet transversely around the bottom and one pair of oppositely disposed sides of said mandrel, distending means spaced from another oppositely disposed pair of sides of said mandrel for cooperating with the latter to maintain marginal portions of the wrapper which extend beyond said other pair of sides in smoothly extending condition, means for folding portions of the wrapper which extend from the bottom of the mandrel upwardly over said other pair of sides of the mandrel, and means for engaging portions of the wrapper which extend from the first mentioned pair of sides of the mandrel to fold the same across said second mentioned pair of sides to complete the formation of the receptacle.

17. In apparatus of the class described, receptacle-forming means comprising a mandrel, means adapted to initially fold a wrapper sheet transversely around the bottom and one pair of oppositely disposed sides of said mandrel, distending means spaced from another oppositely disposed pair of sides of said mandrel for cooperating with the latter to maintain marginal portions of the wrapper which extend beyond said other pair of sides in smoothly extending condition, means for folding portions of the wrapper which extend from the bottom of the mandrel upwardly over said other pair of sides of the mandrel, and means for engaging portions of the wrapper which extend from the first mentioned pair of sides of the mandrel to fold the same across said second mentioned pair of sides to complete the formation of the receptacle, said folding means being adapted to engage the wrapper intermediate the mandrel and said distending means.

18. In apparatus of the class described, the combination of a mandrel, means for folding a wrapper member transversely around the bottom and a pair of oppositely disposed sides of the mandrel, means for receiving the lower end portion of said mandrel with said wrapper so folded therearound, means for yieldingly pressing portions of the folded wrapper against said sides of the mandrel when in said receiving means, means for folding portions of the wrapper which extend from the bottom of the mandrel upwardly over another pair of oppositely disposed sides of the mandrel, and heat and pressure applying means adapted to engage oppositely disposed portions of the wrapper which extend beyond said first mentioned pair of sides of the mandrel so as to fold portions of the wrapper inwardly across said second mentioned pair of sides of the mandrel and to effect sealing of said oppositely disposed portions of the wrapper together to complete the formation of a receptacle.

19. Apparatus according to claim 18 wherein there is provided yieldable means for distending the projecting portions of the wrapper so as to maintain the same in smooth condition to facilitate the bottom-folding and final folding operations for completing the receptacle.

20. In apparatus of the class described, the combination of a mandrel, means for folding a wrapper member transversely around the bottom and a pair of oppositely disposed sides of

the mandrel, means for yieldingly pressing portions of the folded wrapper against said sides of the mandrel so as to maintain the wrapper in position thereon, means for folding portions of the wrapper which extend from the bottom of the mandrel upwardly over another pair of oppositely disposed sides of the mandrel, heat and pressure applying means adapted to engage oppositely disposed portions of the wrapper which extend beyond said first mentioned pair of sides of the mandrel so as to fold portions of the wrapper inwardly across said second mentioned pair of sides of the mandrel and to effect sealing of said oppositely disposed portions of the wrapper together to complete the formation of a receptacle, a pair of plates respectively pivotally mounted adjacent their lower ends and adjacent the bottom of the receptacle, means for rocking said plates toward each other to thereby collapse the upper portion of the receptacle to close the same, and means for folding an upper portion of the receptacle upon themselves to perfect the closure thereof.

21. Apparatus according to claim 20 wherein there is provided means for adhesively uniting the last mentioned folded wrapper portion to another portion of the wrapper so as to provide a sealed, closed receptacle.

22. Apparatus according to claim 20 provided with means for unfolding said plates so as to release the closed receptacle, and means for forcibly ejecting the closed receptacle.

23. Apparatus according to claim 20 provided with means for tucking the end portions of the receptacle inwardly to facilitate the collapsing of the upper portion of the receptacle.

24. In a machine of the class described, a revolvable turret, means revolvable with said turret for forming a wrapper sheet into a receptacle, means carried by and movable with said turret and also turnable independently of said turret for initially receiving a blank from which to form the receptacle and turning said blank to deliver the same in a turned position to the receptacle-forming mechanism, and means for effecting said turning of said receiving means.

25. Apparatus of the class described comprising a rotatable carrier, means for delivering receptacle blanks to said carrier, a hollow mandrel mounted on said carrier for rotation therewith, means movable with said carrier for forming a blank into a receptacle about one end of said hollow mandrel, said hollow mandrel being adapted to permit the delivery of material to be packaged to the receptacle formed on the end of the mandrel, means for effecting withdrawal of the mandrel from the filled receptacle, means movable with said carrier for closing the receptacle, and means for discharging the filled and closed receptacle from the apparatus.

26. In apparatus of the class described, the combination of a hollow mandrel, means for forming a receptacle on one end portion of said hollow mandrel, means for delivering a measured quantity of material to be packaged through said mandrel to said receptacle, means for thereafter closing the receptacle and discharging the same from said forming mechanism, and means for preventing the delivery of said material to the mandrel in the event that a receptacle is not present on said end portion thereof.

27. In apparatus of the class described, the combination of a hollow mandrel, means for forming a receptacle on one end portion of said hollow mandrel, means for delivering a measured

quantity of material to be packaged through said mandrel to said receptacle, means for thereafter closing the receptacle and discharging the same from said forming mechanism, and a detector associated with said receptacle forming means adapted to be actuated by a portion of a receptacle formed on said mandrel, means for locking said material-delivering means against operation, and means controlled by said detector for unlocking said material-delivering means so as to permit operation of the latter when a receptacle is present on said end portion of the hollow mandrel.

28. In apparatus of the class described, the combination of means for forming a receptacle from a blank of sheet material, means for supporting a supply roll of sheet material from which to form said blanks, means for feeding said sheet material from said supply roll, means for creasing said sheet material along predetermined lines, means for severing from the forward end of said creased sheet, wrapper-forming blanks having said creasing thereon in predetermined arrangement for facilitating folding of such severed blanks into receptacle form, and means for delivering said creased blanks to said forming mechanism, said sheet-feeding means comprising spaced pairs of continuously driven feed rollers, and said creasing and severing means being intermittently actuated and requiring temporary stoppage of the feed movement of said sheet material, means actuated in synchronism with the operation of said creasing and severing means for disabling one of said pairs of feed rollers so as to permit the adjacent portion of the wrapper to remain stationary, and means intermediate the other pair of feed rollers and said creasing means for guiding the sheet into arcuate form for taking up the material fed by said continuously operating feed rollers while the forward end portion of the sheet is held stationary.

29. In apparatus of the class described the combination of a vertically reciprocable mandrel, means associated with said mandrel for receiving and positioning a receptacle blank in predetermined position relative to the mandrel, said receiving means being provided with an opening therein adapted to be aligned with said mandrel to permit the latter to be moved downwardly therethrough, means for effecting such movement of said mandrel, thereby to partially fold said blank around the lower end of said mandrel, and means cooperating with said mandrel below said blank-receiving means and while said mandrel remains stationary in lowered position for additionally folding portions of said blank around said mandrel so as to complete the formation of said blank into a receptacle.

30. In apparatus of the class described the combination of a vertically reciprocable mandrel, means associated with said mandrel for receiving and positioning a receptacle blank in predetermined position relative to the mandrel, said receiving means being provided with an opening therein adapted to be aligned with said mandrel to permit the latter to be moved downwardly therethrough, means for effecting such movement of said mandrel, thereby to partially fold said blank around the lower end of said mandrel, and means cooperating with said mandrel below said blank-receiving means and while said mandrel remains stationary in lowered position for additionally folding portions of said blank around said mandrel so as to complete the formation of said blank into a receptacle, said

tubular mandrel serving to permit material to be packaged in said receptacle to be deposited therein while the receptacle remains on the mandrel, means for effecting withdrawal of the mandrel after the receptacle is filled, and means for closing the top of said receptacle after withdrawal of said mandrel and while said receptacle remains in said forming means.

31. In apparatus of the class described the combination of a vertically reciprocable mandrel, means associated with said mandrel for receiving and positioning a receptacle blank in predetermined position relative to the mandrel, said receiving means being provided with an opening therein adapted to be aligned with said mandrel to permit the latter to be moved downwardly therethrough, means for effecting such movement of said mandrel, thereby to partially fold said blank around the lower end of said mandrel, and means cooperating with said mandrel below said blank-receiving means and while said mandrel remains stationary in lowered position for additionally folding portions of said blank around said mandrel so as to complete the formation of said blank into a receptacle, said tubular mandrel serving to permit material to be packaged in said receptacle to be deposited therein while the receptacle remains on the mandrel, means for effecting withdrawal of the mandrel after the receptacle is filled, means for closing the top of said receptacle after withdrawal of said mandrel and while said receptacle remains in said forming means, and means for collapsing the upper portion of the receptacle so as to close the same while it remains in said forming means.

32. In apparatus of the class described, receptacle forming means comprising a mandrel, means adapted to initially fold a wrapper sheet transversely around the bottom and one pair of oppositely disposed sides of said mandrel, said sheet being of such size that when so folded, portions thereof extend beyond the side edges of said oppositely disposed mandrel sides and bottom, and means operative to engage and fold said extending wrapper portions inwardly from the said opposite sides of the mandrel and across other intervening sides thereof, margins of said extending wrapper portions being thereby brought into laterally projecting position relative to said intervening sides and in face to face engagement for inter-attachment to complete the formation of the receptacle.

33. In apparatus of the class described, receptacle forming means comprising a mandrel, means adapted to initially fold a wrapper sheet transversely around the bottom and one pair of oppositely disposed sides of said mandrel, said

sheet being of such size that when so folded, portions thereof extend beyond the side edges of said oppositely disposed mandrel sides and bottom, distending means carried by said mandrel and spaced from other opposed mandrel sides which intervene between said first mentioned opposed mandrel sides, and means adapted to engage said extending wrapper portions intermediate said distending means and said mandrel sides for folding said extending wrapper portions inwardly across said intervening mandrel sides, margins of said extending wrapper portions being thereby brought into laterally projecting position relative to said intervening sides and into face to face engagement for inter-attachment to complete the formation of the receptacle.

34. Apparatus according to claim 18 wherein there is provided yieldable means for distending the projecting portions of the wrapper so as to maintain the same in smooth condition to facilitate the bottom folding and final folding operations for completing the receptacle, and wherein the receiving means comprises pivoted side plates movable toward each other at their upper ends for collapsing and closing the receptacle, and means for securing the upper end of the collapsed receptacle in closed condition.

35. Apparatus of the class described comprising a rotatable carrier, means for delivering receptacle blanks to said carrier, a mandrel mounted on said carrier for rotation therewith, means movable with said carrier for forming a blank into a receptacle about an end portion of said mandrel, means for filling the receptacle, means for effecting withdrawal of the mandrel from the receptacle, means movable with said carrier for closing the receptacle, and means for discharging the filled and closed receptacle from the apparatus, said blank delivering means, receptacle forming, filling, closing and discharging means being distributed around the axis of said rotatable carrier for actuation during a course of travel exceeding one turn of the carrier.

36. In apparatus of the class described, a rotatable carrier, means for delivering receptacle blanks to said carrier, means carried by said carrier for movement in a plane spaced from the plane of said blank feeding means for forming the blanks into receptacles, filling the receptacles, closing and ejecting the filled receptacles, said blank delivery means, receptacle forming, filling, closing and ejecting means being distributed around the axis of said rotatable carrier for actuation during a course of travel exceeding one turn of the carrier.

FRANK D. PALMER.
